a corporation of Pennsylvania

Application February 25, 1947, Serial No. 730,672

16 Claims. (Cl. 198—14)

1

This invention relates to apparatus for transferring coal or like material to a traveling conveyor belt, shaker conveyor line, chain conveyor, pit cars, or the like.

"Shuttle cars" are used in trackless mines to transport coal from the working faces to continuously moving conveyor belts or other conveyor systems, or to cars by which the coal is carried out of the mine or to some remote collecting point. The full discharge rate of "shuttle cars" is such that with a rationally selected conveyor belt, for example, moving at normal rate, there would be overloading of the belt and spillage of coal if such full discharge rate were used. If it is not used, there is loss due to the tying up of equipment at the belt when it might be on its way back to the face or be being actively reloaded at the face; and, even if one "shuttle car" be caused to discharge onto the conveyor belt at a rate sufficiently reduced to avoid overloading of the belt, when it is the sole car delivering to the belt, there will be overloading of the belt if at some other discharge point thereto another "shuttle car" delivers to the belt coal at a rate sufficient to pile up the coal too high on a portion of the belt already loaded nearly to capacity by the first "shuttle car." Accordingly, to secure efficient use of equipment, it is necessary to provide for the discharge of coal from the "shuttle car" at its normal, rapid rate, but to transfer the coal thus rapidly unloaded from the "shuttle car" at a rate such that, under all the conditions that affect the operation of the belt conveyor, or the like, the latter shall not be overloaded.

It is also important in mining to avoid as much as possible the taking of bottom and the shooting of top to provide head room. In the use of "shuttle cars" in conjunction with belt conveyors it has in the past been common to shoot top over the last piece on a butt entry belt conveyor and to build a ramp over the tail piece and to have "shuttle cars" discharge, by means of the ramp, directly onto the belt conveyor, and it would accordingly be desirable to avoid the expense of shooting top and/or bottom and of constructing ramps, especially since each "shuttle car" section has to be moved up at relatively frequent intervals—say every couple of weeks.

It is further important to have equipment that has to be taken underground and set up at a point of use, of light weight, constructed of relatively readily handleable component elements, and to have it capable, after assembly, of being moved, as mining progresses, readily without having to be disassembled again.

2

Low cost is also obviously desirable, as also simplicity of construction; and apparatus which shall not require the constant presence of an operator is highly preferable. Apparatus capable of operating in dips or low places in the mine and whose operation will not be rendered unsatisfactory by reason of the presence of water is also advantageous.

Again, since the number of feeder stations for a single belt conveyor may vary widely, and may change from time to time, the capacity to effect adjustment of the rate of discharge onto the belt conveyor is highly important. For example, if two conveyor loaders have been in operation, and two more are added, the conveyor belt would be overloaded if all four feeder units were to discharge to it at the same time and at the individual rates previously found satisfactory for the two units, wherefore a limitation—a reduction in the rate of discharge of the two units and a restriction in the discharge rates of the added units would evidently be important.

It is among the objects of this invention to provide an improved apparatus for transferring coal from a mine "shuttle car" to a conveyor belt or pit cars at any desired rate, one which can receive the coal from the "shuttle cars" as fast as they can discharge their loads, one which is of a height low enough to be usable in most low seam mines, and one which can be readily taken into the mine and set up, and which can be readily moved as conditions require.

Specifically, it is an object of the invention to provide an improved shaker loader. Another object is to provide an improved shaker loader of improved "knock-down" construction. A further object is to provide an improved shaker loader having improved means incorporated therein for regulating the rate at which it feeds its contents, received periodically at a relatively high rate and in relatively large unit quantities, to apparatus for delivering the material. Still another object of my invention is to provide an improved shaker feeder having an improved construction whereby it is adapted either for close coupling or connection through an extended trough line to a shaker motion-imparting drive mechanism. Yet a further object is to provide an improved shaker feeder having improved supporting and moving arrangements. Other objects and advantages of this invention will hereinafter appear.

As will shortly more fully appear, a coal receiving body may be supported for reciprocatory movement—as by ball frames so mounted as to

facilitate changes in position of said body. The body may desirably include main body and forward or throat portions, the latter connected in use to discharge, generally through one or more trough sections, to a belt conveyor line or some other coal moving apparatus. The connection between said main body and throat sections may be a hinged one, allowing for relative angular adjustment, or a rigid one. The main body portion may desirably be constructed and arranged to facilitate the discharge upon it of a "shuttle car," which may be moved to position its delivery end in overlapping relation with said body, the wall or walls of said body portion being desirably cut away or initially formed to make easily possible the overrunning of a portion of said body by the "shuttle car," to an extent such that the discharging material from the car will fall in a desired position upon said body. Desirably, said forward portion and also said body portion will have wall portions thereon extending transversely to the length of said body, and so angled relative to such length as to give to the coal, when there is relative movement between said wall portions and said coal such as to cause forcible contact between them, a thrust towards the center line of said body, and desirably, when there would otherwise be corners between relatively vertical upright bounding walls and relatively horizontal walls constituting a floor, corner plates will be provided on an inclination so that they shall prevent packing of wet fines, and impart a lifting, centering action to the coal. Motion will be imparted to the contents of the body by means for imparting to the body relatively slow and relatively uniform forward movements in alternation with relatively sharp rearward movements, as by means of an independently powered shaker conveyor drive connected to said throat section or to the pan or trough line to which the forward end of said body is secured, or by a drive of like characteristics securing its power through a bell crank actuated by a transversely extending shaker conveyor line or from the rearmost guide roller of a belt conveyor, as, for example, when the shaker feeder is in alinement with and overlaps the end of the belt conveyor to which it delivers coal. Desirably, the forward section of the body may include a trough section having in it a gate or choke plate upwardly adjustable about a horizontal transverse axis for the purpose of providing means for controlling delivery rate, but control of the rate of feeding of coal from the coal receiving body will also be designed into the feeder, in the shaping of the side plate portions, which perform the combined functions of preventing spillage over the sides of the body and of thrusting the coal towards the center line of the body as the passage of the coal therefrom provides space to receive the coal from the sides of the body, or by the provision of other devices for laterally diverting the coal; and feed rate control may also be secured by angling of the forward body portion relative to the main body portion. Desirably, the bottom of both portions of the body may be covered partially or wholly with plates provided with projections shaped to facilitate their rearward movement beneath the coal and to cause their forward movements to impart thrusts to the coal in a forward direction.

In the accompanying drawings, in which, for purposes of illustration, a preferred embodiment and a modification of the invention are shown:

Fig. 1 is a plan view of an embodiment of the presently preferred form of the invention, show-

ing the same loading onto a belt conveyor line.

Fig. 15 is a somewhat diagrammatic view showing drive of the shaker feeder through a bell crank from a transversely extending shaker conveyor line to which the feeder discharges.

Referring to the drawings, and first to Figs. 1 to 9 thereof, a coal-receiving body, generally designated 1, is formed of two principal portions, a main body portion 2 for receiving material from a "shuttle car," and a forward or throat portion 3 for connection with, and for the delivery of coal to, a shaker conveyor pan or trough line 4. The pan line 4 is shown as extending to a belt conveyor line 5, upon which it is adapted to discharge, but could obviously discharge to other suitable devices; and is shown as actuated by a shaker conveyor drive mechanism 6, which may be, for example, of a construction such as is illustrated in my patent application Serial No. 715,526, filed December 11, 1946. The pan or trough line, and the ball frames 7 which support it for reciprocatory movement, are of conventional construction, and the length of the pan line is extensible as need occurs for moving the loading station—the point at which "shuttle cars" unload their coal—upon the body 1. The body 1 is supported and guided for longitudinal reciprocatory movement by suitably positioned ball frame 7', whose upper portions 9 are secured to the bottom of the body 1, while their relatively movable lower portions 10 are mounted upon skid plates 11 so that the body 1 may be slid over the mine bottom upon the skid plates 11, when bodily movement thereof is called for, as by being hauled by a "shuttle car."

In order that the body 1 may be gotten into the mine without undue difficulty, its forward

portion 3 is made detachable from the main body portion 2 and the latter is desirably made up of two sections 12 and 13, each constituting a lateral half of the body portion 2 and secured rigidly with respect to each other by bolts 14 engaging with nuts 15 welded to transverse channel irons 16 extending transversely beneath the bottom plates 17 of the main body portion 2. Each of the body sections 12 and 13 carries at its forward end a section of a piano type hinge structure 18, and the rearward end of the front section 3 is provided with a coacting hinge structure 19 which is secured in interfitting relation with the hinge structure on the body sections 12 and 13 by pin means 20.

The forward portion 3 consists of a progressively narrowing body section 21 and a discharge passage section 22 rigidly connected together so that they pivot as a unit on the line of the axis of the hinge pin 20; and the discharge passage section is supported on a ball frame 7", also skid-mounted as at 11.

With the body construction described and shown, it is contemplated that the "shuttle car" shall move into discharge relationship to the shaker loader by movement directly in line with it, and the wall arrangement of the body provides for this. The rear ends of the bottom plates 17 are turned down slightly at 25, to insure against interference with the bottom of a "shuttle car" moving into discharge position. Moreover, the rearward end of the main body portion 2 and the rearward portions of the side edges thereof do not have side walls associated with them when coal delivery is to be over the rear end. The greater length of the main body portion 2 is provided with side walls, however, as is also the front or throat portion 3. These side walls are provided for the plural purposes of increasing the receiving capacity, preventing spillage, and causing the coal to be moved into line with, and therefore, be discharged through, the discharge passage section 22. Considering first the walls 26, 26 at the opposite sides of body portion 2, it will be noted that these are parallel to each other and vertical, from the forward ends of the plates 17, 17 rearwardly for something over half the lengths of their respective plates. The upper sections of the vertical walls 26 then diverge rearwardly as at 27, 27 and again become parallel as at 28, 28. Oblique, triangular plate sections 29, 29 are secured at two edges respectively to the wall portions 26 and 27 and to inwardly sloping sections 30, 30 extending from the plates 17, 17 to the wall sections 28, 28. Thus capacity is increased, movement of any coal standing on the sloping sections 29, 29 and 30, 30 into the space between the walls 26, 26 is assured, and the lodging of wet fines in any pockets coming to sharp corners is avoided.

To prevent escape of coal over the top of the vertical side walls 26, 26, as the coal commences to back up as later described, inwardly sloping wall portions 31, 31 may be secured to the tops of the forward portions of said vertical walls.

The forward body portion 3, hingedly connected to the main body portion 2, as previously described, narrows from the full width of the forward end of the body portion 2 to the relatively narrow width of the entrance to the discharge passage portion 22. The latter is of a substantially uniform width for a substantial distance from its rear end, and is integrally connected to the narrow forward end of the tapered section of the forward body portion 3.

The portion 3 has vertical side wall portions 36, 36, which converge from the forward ends of the vertical walls 26, 26 rather gradually, and these walls 36, 36 are joined to other vertical wall portions 37, 37 which converge considerably more sharply. Triangular plates 38, 38 are disposed with their lower edges making an angle on the order of 60° with the bottom plate 38' of the rearward part of portion 3, and are secured to the latter at 39, 39, and along one higher edge are joined at 40, 40 to the wall portions 37, 37 while their other higher edges are joined at 41, 41 to a sloping edge of the vertical plates 36, 36 whose remaining lower edge portions are secured at 42, 42 to the bottom plate plate 38'. Sloping plate portions 44, 44 comprising angularly related parts 45, 45 and 46, 46 are arranged at the tops of the vertical wall portions 36, 36 and 37, 37, and parts 46, 46 are connected at their forward ends to the side board portions 47, 47 on the delivery trough, while the parts 45, 45 are connected to the wall portions 36, 36, and the junction between the parts 45, 45 and 46, 46 is along lines 48, 48 extending transversely from the top of the line of junction of the vertical wall portions 36, 36 and 37, 37. The forward end of the delivery section 22 narrows at its lower portion to conform to the shape of the trough line 4 to which it is bolted. Vertical side walls 49 are narrowed to shallow strips 50, 50 at their tops and are connected at the forward end of the delivery section to sloping plates 51, 51, whose bottom edges are joined at 52, 52 to the narrowed forward end 53 of the bottom plate 38'. Triangular plates 54, 54 are connected along oblique lines 55, 55 to the plate section 53 and also to the plates 51, 51 and to the parallel side plates of the discharge. These oblique plates prevent wet dust from lodging in any corners and divert the coal into the narrow-bottomed forward end of the delivery passage. Sloping side board portions 47, 47 are carried by the tops of the side walls 49 and connected with the side board portions 46, 46. Gusset plates 59, 59 are arranged at the opposite outer sides of the body portion 3 to stiffen the construction and enable it to stand up under the severe punishment that the heavy masses of coal thrusting against the walls 37 and 38, and the walls 36 impose on the structure. These are welded, as shown, along the outside of the junction of plates 37 and 46, extended obliquely downward along the outside of the side plates, to which they are welded, and terminate at the junction point of the side plates, the bottom plate, and the oblique triangular plates 54, 54.

A gate or choke device 60, in the form of a choke plate 61, whose rearward end is hinged at 62 to the bottom plate 38' is swingable upwardly about this hinge connection, and is adapted to be fixed in various angular positions by a rod or long bolt 63 received in holes 64 arranged in arcuate series in the vertical walls 49, 49, and in tubular elements 65 fixed to the bottom of the front end of the choke plate 61. Flanges 66, 66 outwardly sloping from the tops of the upright side walls serve as spill boards to prevent spillage of coal in the event the passage 22 is overfilled.

At the forward ends of the side walls 26, 26 of the main body 2 there are upright, inwardly bent flanges 67 which cooperate with the side plates 36 in preventing escape of coal at the relatively movable walls overlying the hinge. Anti-

spread bars 68, 68 are welded on the upper edges of the outer sides of the plates 26, and prevent the rearward edges of the plates 36 from spreading under the action of the coal upon the reversals of movement which occur as the rapidly accelerated rearward movements of the body take place. Bolts may be passed through holes 68' in the anti-spread bars 68, in the flanges 67 and in the plates 36 to lock the main body portion 2 and throat portion 3 rigidly together when desired.

The ball frames previously described are secured to the bottoms of the body portions 2 and 3 by T-shapes 69 welded to the bottom plates 17, 17 and 38' respectively, and arranged and held between the uprights of angles 64, secured to the tops of the ball frames. There are four ball frames in a rectangular arrangement, beneath the body portion 2, two beneath each lateral half, and there is a single, centrally disposed ball frame beneath the body portion 3.

The bottoms of the body portions of the discharge section and of the pan line may all desirably be provided with lag plates having projections for the purpose of promoting their pushing of the coal in a forward direction only. One plate 17 carries a lag plate overlapping the other.

The means for reciprocating or providing a shaker action for the body 1 and the trough line 4 may assume different forms, and actuation may not only be directly by shaker drive mechanism such as the one shown at 6, but may also be by actuating forces from the conveyor line which the shaker feeder feeds, as shown in Figs. 10 and 11 where the belt conveyor 70, to which the end of the trough line 4 discharges, has a relatively heavy guide roll 71—heavy enough to perform a flywheel function, and this roll, through belt 72 or other suitable driving connections, operates a shaker spring and lever mechanism 73 similar to the corresponding parts of the mechanism 6. Obviously it would also be possible to effect drive of the shaker feeder through a bell crank operated by a shaker conveyor line receiving the discharge from the shaker feeder, when the latter is delivering material to an angularly related shaker conveyor system. For an illustration of this, see Fig. 15.

It is, of course, understood that where serially arranged conveying devices are employed means is provided of such nature that derangement of any subsequent conveyor section or element effects automatic interruption of the operation of the preceding devices in the path of material movement; and, while such a mechanism per se forms no part of my invention, a control of this kind may commonly be used with it.

The mode of operation of my invention will be readily understood from the description of its construction which has been given. Referring to the embodiment shown in detail in Figs. 1 and 8 and in operation in Figure 9, and referring momentarily first to the view of Figure 9, it will be noted that the body 1 delivers material to the trough line 4, and, with its trough line 4, is actuated by the shaker drive mechanism 6, and discharges to a belt line or other suitable conveyor system 5 (though it might also discharge to cars), and that a "shuttle car" 75 is in a position with its discharge end 76 overlying the rearward end of the body portion 2. In practice the amount of overlap may be 18 inches or more, and because the "shuttle car," in discharging its contents rather rapidly, imparts a substantial momentum

to the material, and because the conveyor discharge is usually well above the bottom of the body 1, there will be a very good distribution of the mass of material over the bottom of the body 1, a portion of the material landing ordinarily as far back as the most widely separated walls 28 and being distributed quickly entirely over the body bottom. Desirably the body 1 will be in motion as the material is being dumped onto the body bottom from the "shuttle car" or the like, but this is not necessary, as the apparatus is capable of being fully loaded with the contents of a "shuttle car" and still be set into motion and unloaded although it may be stationary at the moment of material discharge upon it.

As the body is moved alternately smoothly and at a slow velocity in the forward direction and more rapidly and with sharp acceleration in a rearward direction, the material contained in the body will be bodily moved with the latter on the forward motions of the body and will tend to be stationary, or even to continue its forward motion, while the body bottom is shoved sharply beneath it in the rearward direction. As the mass of coal moves forward it spreads over the full width of the body, and as it moves forward the central portion of the mass must move ahead in order that loading may occur. Whether the entire central band of coal moves out first or whether, more probably, the forward central portion moves out and the coal from the wide sections moves into the edges of the central more rapidly moving mass, in any event, there will be a substantial control of velocity inherent in the general design, because the working of the mass on itself will measurably retard the edges at least of the portions which are traveling into the discharge passage. This will not be adequate ordinarily to provide the desired limitation on velocity, and reliance may be placed on the restriction of the speed of movement by requiring the coal to move up a gradient on its way to discharge. For example, the choke plate may be adjusted to retard flow.

The convergence of the side walls constitutes an inbuilt control of, or at least restriction of, discharge rate, and it may be said that a substantial control of the speed of discharge is built into the design of the body by the proper inclination and proper angles of the inclined surfaces heretofore described. Moreover, when loading with a very close-coupled relation of the shaker feeder to the shaker drive 6, there will be a considerable inclination of the forward discharge section or throat 3 of the main body 1, and this inclination, supplemented perhaps by some inclination of the choke plate, will also operate to provide a reduction in the speed of discharge. While absolute prediction of precise arrangements is impossible in view of the varying nature of the coal to be discharged, its wetness or dryness, and other factors, it may be said that in some cases neither inclination of the throat nor tilting of the choke plate will be necessary to maintain the desired control of discharge velocity. In other cases, where the entire body 1 is horizontal, various inclinations of the choke plate may be indicated, and where the body is close to the shaker drive mechanism 6 the inclination of the throat or forward portion 3 of the body may at times provide all of the retarding effect necessary, but it may be supplemented by the action of the choke plate. In general it may be expected that as the distance between the body 1 and the drive 6 reduces the tilt of the throat 3, there will be

likely to be increased need for reliance on the retarding action obtained by the lifting of the end of the choke plate.

As previously indicated, flanges 67 cooperate with the plates 36 in preventing the escape of material through the adjustable fit between the main body and throat sections, and the anti-spread bars preclude the spreading of the side walls of the throat portion as the heavy mass of coal entering the tapering space in the throat section tends to force said walls apart. 10

The ball frames which underlie the body and the throat section provide for the very smooth and easy reciprocation of the parts which they support, and when the throat section is tilted upwardly the ball frame 71 which underlies it in its then inclined position will be blocked up. It will be understood that while the mechanism is very ruggedly built there is in all shaker conveyor equipment a certain degree of play which makes unnecessary any special hook-up with respect to the forward ball frame when the same is blocked up. 15

When it is desirable to change the position of the loading station it is simply necessary to disconnect the shaker feeder from the drive 6, or, if there are intervening trough sections, from the closest trough section, and by connecting a "shuttle car," by means of a chain or cable to the body 1, as to eyes 77 in the bottom plates of the body 1, the entire shaker feeder can be drawn to its desired new position. The ball frames slide freely, due to the up-tilted ends of their skid plates, during this bodily movement. 20

The mode of operation of the arrangement of Figs. 10 and 11 differs from that which has been perhaps more fully explained only in such details as result from the fact that the discharge trough extends in the same direction with the conveyor 70 and discharges longitudinally of it instead of transversely to it, and that the power for the shaker feeder is transmitted through the belt 70 to the heavy roller 71 and by the latter to the arm and spring shaker mechanism 73. 25

In Figures 12, 13 and 14, I have illustrated another modification of my invention in its broader aspects, in which modification there is no pivotal connection between main body and throat sections; instead the entire shaker feeder, from its end over which material is dumped to its other end, is one rigid unit, and in which modification there is wholly inbuilt the rate of discharge control, and no adjustable choke plate or equivalent adjustable device is incorporated. This modification is illustrated (see Fig. 15) with actuation through a bell crank from a transversely extending shaker conveyor line to which it is shown discharging. 30

In order that this shaker loader can be taken into the mine with less difficulty, it is made in three separable parts: two body portions, 81 and 82, cooperating to form a material receiving body 83, and a throat or delivery section 84. The body portions 81 and 82 may have angle irons 85 welded or otherwise suitably secured along their edges which adjoin each other when the body 83 is assembled and which are adapted to have their vertical flange portions 86 bolted together as at 87. The throat section 84 is adapted to be bolted to the body portion 83 by bolts 88 extending through the bores of short pipe sections or the like 89 and 89' respectively secured, as by welding, to side walls 91 and 92 extending along the outer sides of the body portion 83 and throat section 84. An angle iron 90 is welded to the 75

bottom of the throat section 84 and underlies the forward ends of the bottoms of the body portions 81 and 82. The side walls 91 are provided to increase the receiving capacity of the body portion 83, and both the side walls 91 and 92 are provided to avoid material escape over the sides of the feeder. Moreover major portions of the side walls 91 and 92 serve to direct the material towards the discharge from the throat section 84. 10

The side walls 91 conform to the edges of the body portion 83; and the latter has parallel, widely spaced edges 93 at its receiving end upon which parallel portions 94 of the side walls 91 are mounted. The portion of the body portion 83 towards the throat portion 84 has converging edges 95 upon which converging portions 96 of the walls 91 are mounted. The throat section 84 has converging edges 97 throughout most of its length and terminates in a relatively short parallel-edged portion 98; and the side walls 92 comprise upright converging sections 99 extending to the portion 98 and parallel upright sections 100 along the sides of the portion 98. The spacing between the walls 100 is such as to provide a passage 101 of suitable width to discharge onto a conveyor trough 102. It will be observed that an inclined triangular plate section 104 connects the bottoms of the wall sections 99 with the side edges 97, which form a larger included angle than the dihedral angle between the upright side walls 92. Similarly, inclined plate sections 105 connect the bottom edges of the upright wall sections 100 with the relatively narrow plate 106 which forms the bottom of the portion 98, the plate sections 104 and 105 being, as desired, integrally formed with each other or welded together. As above stated, the main bottom plate section 107 of the throat portion 84 has its edges leading to the plate portion 106 converging more rapidly than the upright walls 92. 25

To control the rate of discharge, a central upright plow-like obstruction 111, in the form of plates 112 making a right angle with each other and with the edge 113 of the angle directed against the moving mass of coal on its way to the discharge, is arranged in the throat section 84, being welded or otherwise suitably secured near the wide end of the plate 107, to the latter. Two other flow directing plates 115, 115 are suitably secured, as by welding, to the side plates 92, 104 and to the bottom plate 107, and converge much more rapidly than the side plates 92. 30

The top edges of the plates 92 and of the plates 115 support inwardly sloping (inclined) plate sections 116 and 117 respectively, which prevent upward coal escape over the top of these upright plate sections, as the forwardly thrusting mass of coal forced by the converging walls into a constantly narrowing stream tends to overflow the tops of the walls. These plate sections 116 and 117 direct the upwardly thrust coal back towards the center line of the feeder. 35

A bell crank 120 pivoted on a jack 121 transmits shaker motion from the main line troughing to the pivotal connection 122 fixed as shown to the trough line 123 which is bolted at 124 to the forward end of discharge section 98. See Figure 14. 40

Four ball frames, 125, 126, 127, and 128, are disposed in rectangular arrangement under the body portion 83, and one, 129, laterally centrally, but near the forward end, of the throat section 84. 45

The mode of operation of this embodiment of the invention is essentially as follows. The main

line troughing transmits through the bell crank 120 movements to the shaker feeder consisting of alternate relatively slow and smooth movements in the direction of discharge and faster, sharply accelerated movements in the opposite direction. As a result coal discharged at a relatively rapid rate onto the body portion 83 is rapidly spread forwardly over the entire bottom area and fed in steps of several inches each towards the discharge. To the prevention of a rate of discharge such as to exceed the carrying capacity of the trough line, the converging side walls, the obstructor 111, and the plates 115 will all contribute. The plates 115 may be considered as a metering device—a weir, if such a term can be used with reference to so un-uniform a stream as shot and loaded coal. The device 111 will restrict the width of the passages at its sides and obstruct and deflect the central course of the coal, and the converging side walls will frictionally retard coal movement and through forcing the lateral portions of the mass towards the center will contribute to the avoidance of excessive rates of discharge. It will also be noted that the freedom of the columns of coal to expand behind the device 111 will permit a further reduction in the rate of coal movement between the device 111 and the plates 115. With coal without too large lumps this particular arrangement can do a very efficient job of feeding coal rapidly received from a "shuttle car" or the like to a trough line at a unit rate calculated to utilize the trough line at maximum efficiency.

A point worth noting with respect to my invention in its embodiments driven through a spring and arm shaker drive is that the power consumed thereby and the wear and tear on it are both directly proportional to the coal being loaded. When a load of several tons is deposited in a matter of a relatively few seconds upon the bed of the receiving hopper, the springs of the shaker drive undergo relatively heavy compressions and the throwing action of the shaker loader is very pronounced and the rate of material movements high. As the coal is all gotten onto the trough line and the load on the latter diminishes as the coal is delivered to the belt conveyor or the like, the spring compression is diminished, and if the shaker feeder gets its entire load discharged, then the springs do not compress markedly at all, and the motion of the receiving body and of the delivery trough section becomes merely one of uniform reciprocation, thus saving not only power but also wear and tear on the equipment.

The advantages of my invention and the features which cause it to provide a superior action have been so fully discussed above that a recapitulation at this point is unnecessary. Each of the embodiments very effectively meets the conditions for which it is especially designed, and in all embodiments thereof coal (or other material) may be received in rather large quantities in very short periods of time and be fed out to a desired point of discharge over a longer period of time and at a reduced rate, and the discharge rate may, in the embodiment of my invention first described, be adjusted to provide uniform discharge rates suited to widely varying conditions.

While I have in this application specifically described two forms and various modifications which my invention may assume in practice, it will be understood that these forms and modifications are shown for purposes of illustration

and that the invention may be further modified and embodied in various other forms without departing from its spirit or the scope of the appended claims.

5. What I claim as new and desire to secure by Letters Patent is:

1. A shaker conveyor feeder for receiving material periodically in large volumes and feeding it gradually to a shaker conveyor line, said feeder comprising, in combination, a material receiving body terminating in a relatively narrow discharge trough section and open at its top throughout its length for the reception of material, means for reciprocating said body and discharge trough section imparting to them relatively slow, smooth movements in the direction in which said trough section extends from said body and relatively sharply accelerated, more rapid movements in the opposite direction, in alternation, means for supporting said body and discharge trough section for such reciprocation, material deflecting means carried by and fixed with respect to and forming a part of said body for directing material on said body from the side portions thereof towards the center thereof, and ultimately into the width of the shaker conveyor line, as such material is moved by the action thereon of said body, and means for requiring material to ascend a gradient to limit the rate of discharge thereof, the depth of said body between said material deflecting means substantially exceeding the depth of the shaker conveyor line.

2. The combination defined in claim 1 in which the means for requiring material to ascend a gradient includes an upwardly tiltable plate at the mouth of said discharge trough section.

3. Apparatus for receiving coal from a shuttle car and for transferring coal so received at a slower unit rate to a point of delivery, including a relatively wide coal receiving body, a relatively narrow pan line extending from said body to a point of delivery, said body and said pan line both open at their tops, means for effecting a restriction in the rate of flow of coal from said body to said point including an angularly adjustable gate swingable upwards at its forward end about a horizontal axis and positioned to be traversed by the coal before it leaves said body and reaches said pan line, and means for actuating said pan line and said body including means for imparting to both of them alternate fast rearward movements and slower forward movements.

4. Apparatus for receiving coal from a shuttle car and for transferring coal so received at a slower unit rate to a point of delivery, including a relatively wide coal receiving body, open at its top and having a forward and a rearward portion, a relatively narrow pan line extending from said body to a point of delivery, the forward portion of said body connected to the rearward portion thereof on a horizontal transverse pivot and tilted upward relative to said rearward portion and having laterally converging walls and secured to said pan line, the lateral convergence of said walls and upward tilt of the forward portion of said body about said horizontal pivot coacting to restrict the rate of flow of coal from said body to said pan line, and means for actuating said pan line and said body including means for imparting to both of them alternate fast rearward movements and slower forward movements.

5. A shaker conveyor feeder comprising, in combination, a material receiving body having a relatively wide material receiving compartment

opening at its forward end into a parallel walled discharge channel, means for supporting the same for longitudinal reciprocation, means for imparting thereto a reciprocating shaker feeding movement, and means moving with, but stationary with respect to, said body as the latter reciprocates and adjustable with respect to the latter to provide a slope in the bottom thereof and arranged at the point of entry of material to said parallel walled discharge channel for limiting the rate of flow into the same.

6. In a shaker conveyor feeder for receiving material at a rapid rate from material transport cars and delivering it to a point of discharge at a slower rate, a material-receiving trough having at its rear end a flat bottom portion extending for the full material receiving width thereof and, both laterally and at its rear, free of walls obstructing movement inwardly across its borders in planes close to its upper surface, said trough having forwardly of said rear flat bottom portion side walls including parallel upright portions and, forward of such parallel portions, portions converging towards a discharge opening, and means for imparting a reciprocating shaker motion to said trough, said receiving trough being wider than the discharge of a material transport car from which it is designed to receive material and having, by reason of the absence of walls at its rear end, its upper surface accessible to the discharge of such a car when the latter is in alignment with the longitudinal center line of said trough, or oblique to said center line, or has its own center to one side of said last mentioned center line, and supporting means for said trough for maintaining it so low as to have the bottom of such a car overlie it, when such car and said feeder are supported on surfaces in a common plane.

7. In a shaker conveyor feeder, a body having a main portion for receiving material and having a front discharge portion, said portions separately movable into a mine, and means for connecting said portions for use in the mine, said main portion comprising a pair of initially mutually separate lateral halves and said front discharge portion being of unitary construction for its full width at its end nearer said main portion, said lateral halves being rigidly connected together when said body is assembled, means for hingedly connecting said discharge portion to the forward ends of said rigidly connected lateral halves in a position with like portions thereof opposite each of said lateral halves, and means for guiding and supporting each of said lateral halves and said discharge portion for reciprocation as a unit, in a path extending longitudinally of said body.

8. In a shaker conveyor feeder, a body having a main portion for receiving material and having a front discharge portion, the latter diminishing in width forwardly, said portions separately moveable into a mine, one of said portions comprising a pair of lateral halves rigidly connected together when said body is assembled and the other being at one end at least substantially of the full combined width of the adjacent ends of said lateral halves and hingedly connected to both of said rigidly connected lateral halves, and ball frames underlying each of said lateral halves and said hingedly connected portion respectively and having their guideways arranged lengthwise of said body whereby the latter is reciprocable longitudinally as a unit.

9. In a shaker conveyor feeder, a material-receiving main body section, a throat section to and over which material is dischargeable, means for optionally rigidly connecting said sections together or hingedly connecting them together upon a horizontal transverse axis said sections in each case having their longitudinal axes parallel to a vertical plane extending longitudinally thereof, and means for imparting to both of such sections as a unit a shaker type of reciprocation in a direction longitudinal thereof.

10. In a shaker conveyor feeder, a material-receiving main body section, a throat section to and over which material is dischargeable, each of said sections having bottom and side walls, means for connecting said sections including a pivotal connection between said bottoms and spread-limiting sliding connections between the top portions of said side walls, and means for imparting a shaking motion to said sections in a direction longitudinal thereof to effect their reciprocation horizontally as a unit.

11. A shaker conveyor feeder comprising a body portion presenting a wide, substantially flat, material-receiving bottom surface and having between its ends, upstanding, initially widely spaced, then inwardly converging, wall portions, and having relatively parallel upstanding walls extending from said converging walls to its forward end, and a forward portion having upstanding converging walls and connected to said body portion, said forward portion having a discharge passage section at its end remote from said body portion.

12. In a shaker conveyor feeder device, a material-receiving body and a relatively narrow discharge passage forming means, means for supporting the same for reciprocation together, means for imparting a reciprocatory movement to the same including relatively smooth forward movements and relatively sharply accelerated backward movements, and means for controlling the rate of material delivery by said shaker conveyor feeder device including a choke plate arranged at the rearward end of said relatively narrow discharge passage forming means and having its rearward end pivoted and its forward end upwardly swingable, and means for underlying and supporting said forward end selectively at a number of different fixed heights.

13. In a shaker conveyor feeder, a body having a main portion for receiving material and having a front discharge portion, said portions separately movable into a mine, and means for connecting said portions for use in the mine, said main portion comprising a pair of lateral halves and said discharge portion being, at its own end adjacent said main portion, of the full width of the adjacent end of said main portion, said lateral halves being rigidly connected together when said body is assembled, means for hingedly connecting said discharge portion to the forward ends of said rigidly connected lateral halves, supplemental means for effecting rigid connection between said discharge portion and said main portion, and guides, including relatively reciprocable elements respectively adapted to rest upon a subjacent surface and secured to and supporting said body, for guiding said body for horizontal reciprocation, each of said portions having certain of said guides underlying it.

14. A shaker conveyor feeder for intermittently receiving material in considerable volume from mine transport vehicles and for feeding it, so

long as it is available, to a shaker conveyor trough line, said feeder comprising an open topped body having beneath the same ball frames, including ball frames at its forwardmost end and ball frames at its rearward end, said body having an open rear end, and wide at its rearward end, and at its forward end of substantially the width of the shaker conveyor trough line, and having side walls considerably higher than the depth of the trough line and having converging portions for crowding material upon said body towards the center line of the latter as it moves therealong, and means for moving said body forwardly to carry with it a superimposed load of material, and rearwardly, at a more rapid rate, beneath the superimposed load.

15. In a shaker conveyor feeder, a body having a main portion for receiving material and having a front discharge portion, said portions separately movable into a mine, and means for connecting said portions for use in the mine, one of said portions comprising a pair of initially mutually separate lateral halves and the other being, at its end nearer said halves, unitary throughout its full width, said lateral halves being rigidly connected together when said body is assembled, means for hingedly connecting said other portion to the adjacent ends of said rigidly connected lateral halves, including hinge connections with each of said halves, supplemental means for effecting rigid connection between said portions, and guides, including relatively reciprocable elements respectively adapted to rest upon a subjacent surface and secured to and supporting said body, for guiding said body for horizontal reciprocation, each of said portions having certain of said guides underlying it.

16. In a shaker conveyor feeder, material receiving and discharge devices forming a plurality of side-walled transverse zones each disposed half at either side of the longitudinal center line of said material receiving and discharge devices and each connected by converging wall portions with a narrower zone forward of it, each of said converging wall portions including a sloping polygonal plate having a horizontal edge oblique to said center line for avoiding sharp corners in which material could collect.

CHARLES NEWTON BEBINGER.
